UNITED STATES PATENT OFFICE.

EDWARD A. HEMPHILL, OF ELIZABETH, NEW JERSEY, ASSIGNOR TO THE KIGGINS AND TOOKER COMPANY, OF NEW YORK, N. Y.

MEMORANDUM-BOOK.

SPECIFICATION forming part of Letters Patent No. 285,618, dated September 25, 1883.

Application filed April 23, 1883. (No model.)

To all whom it may concern:

Be it known that I, EDWARD A. HEMPHILL, of Elizabeth, in the county of Union and State of New Jersey, have invented a new and Improved Memorandum-Book, of which the following is a full, clear, and exact description.

My invention relates to improvements in memorandum-books; and the invention consists in a memorandum-book having its covers 10 stitched to each other a short distance from the back, forming a pencil-pocket along the back of the book, all as hereinafter fully described.

Reference is to be had to the accompanying 15 drawings, forming part of this specification, in which similar letters of reference indicate corresponding parts in both the figures.

Figure 1 is a perspective view of my improved memorandum-book. Fig. 2 is a cross-sectional elevation of the same on the line xx , Fig. 1.

The memorandum-book A is provided with the covers B in the usual manner, and along the back of the book—that is, along the joint 25 of the covers—a pencil-pocket, C, is formed, which is outside of the back—that is, it is not between the back of the book proper and the back of the cover, but the back of the cover is between the back of the book proper and the

pocket C. Preferably both covers are made 30 in one piece, and the pocket is formed by stitches a short distance from the back, and the book is then pasted to the covers. The pencil in the pocket stiffens the book and prevents it from being doubled over or bent, and 35 does not interfere with using the book and turning the leaves, and is entirely out of the way when not in use.

Having thus fully described my invention, what I claim as new, and desire to secure by 40 Letters Patent, is—

1. A memorandum-book having its covers 45 stitched to each other a short distance from the back, forming a pencil-pocket along the back of the book, substantially as herein shown and described, and for the purpose set forth.

2. The combination, with two book-covers 50 stitched to each other a short distance from the back, thereby forming a pencil-pocket, of a book held between and secured to the covers in such a manner that the pencil-pocket will be along the back of the book, substantially as shown and described.

EDWARD A. HEMPHILL.
